UNITED STATES PATENT OFFICE.

SIGMUND FREY, OF LOS ANGELES, CALIFORNIA.

CAN.

Application filed March 28, 1923. Serial No. 628,211.

To all whom it may concern:

Be it known that I, SIGMUND FREY, a citizen of the United States, residing at Los Angeles, in the county of Los Angeles and 5 State of California, have invented a new and useful Can, of which the following is a specification.

This invention relates to cans of the type employed for holding garbage, lard and 10 other substances.

An object of the invention is to so construct the cans that they may be readily superposed to form a straight tier of cans that will be secure against toppling over.

15 Another object is to detachably secure the covers to the can bodies by a comparatively simple device.

A further object is to make provision for automatically forcing up the lid by 20 operation of the bail of the can.

The accompanying drawings illustrate the invention:

Figure 1 is an elevation showing superposed cans constructed in accordance with 25 the provisions of this invention.

Fig. 2 is an enlarged fragmental sectional elevation of the cans shown in Figure 1.

Fig. 3 is a fragmental elevation, partly in section, showing the can provided with a 30 modification of the device for detachably holding the cover in place.

Fig. 4 is a view similar to Figure 3 showing the can provided with a still different modification of the device for detachably 35 holding the cover in place.

Fig. 5 is a view similar to Figure 3 showing the can cover provided with a modification of the device for detachably holding the 40 cover in place.

Fig. 6 is a fragmental side elevation of one of the cans shown in Figure 1 with the bail raised into position to loosen the cover.

Fig. 7 is a sectional elevation of Figure 45 6.

Fig. 8 is a fragmental side elevation, similar to Figure 6, showing a modification of the means for engaging and lifting the cover.

Fig. 9 is a sectional elevation of Figure 50 8.

The tubular body 5 of the can may be circular or of any other suitable form, and is provided with a flanged bottom 6, the flange being indicated at 7. In the instance shown, the bottom 6 is connected with the 55 body 5 by a double seam 8.

The upper end or rim of the body 5 is

formed with the usual rounded bead or roll 9, and removably seated on said bead is a cover 10. The portion of the cover 10 that engages the bead 9 constitutes a rim-engaging seat 12 that lies between a shoulder 13 and a flange 14 of the cover. The edge of the flange 14 may be finished with a bead or roll 15. The outside diameter of the shoulder 13 is slightly less than the inside 60 diameter of the flange 7 so that the bottom of a similarly constructed can will fit over the shoulder 13 and rest on the seat 12, as in Fig. 1, thus enabling the cans to be readily 65 stacked one on another for shipping and 70 storing. The cover 10 is downwardly dished, as indicated at 16, and is provided on the dished portion with a suitable handle 17. The dishing of the cover is sufficient to permit the handle 17 to be contained between 75 the cover and the bottom of the other can that is seated on the cover, as clearly shown in Figure 2. To increase the clearance between the handle of the can below and the bottom of the can above, if desired, the bottom 6 of the can may be recessed upwardly, 80 as indicated at 18.

Fastening devices are provided for detachably retaining the cover in place on the can body and such devices may be variously 85 constructed at the time that the cover is stamped, the devices preferably being produced by a punching or pressing operation. In Figures 1 and 2 are illustrated fastening devices constituted by inwardly projecting 90 punches or beads 19 in the flange 14 of the cover. The punches 19 are formed by indentations in the flange 14 just beneath the bead 9 and they engage the under side of 95 said bead so that considerable effort is required to remove the cover from the can body. However, the punches 19 are rounded so that they will readily pass the bead 9 when applying or removing the cover. The fastening devices hold the cover securely enough for shipping and to prevent 100 displacement of the cover by dogs or other animals. In Fig. 5 the punch 191 is continuous to form an inwardly projecting rounded bead extending entirely around the 105 lid flange.

In Figure 3 the fastening devices for the cover are constituted by punches which form tongues 20 cut from the flange along three edges of the tongue and pressed or stamped 110 inwardly from the cover flange 14 so as to lie beneath the bead 9, the tongues extend-

ing at right angles to the longitudinal axis of the can and the upper edges of the tongues engaging the under side of the bead 9. The bead 9 being rounded enables the tongues 20 to slip past said bead when the cover is applied or removed.

In Figure 4 the fastening devices are constituted by inwardly extending punches which form rounded or convex projections 10 21 that are cut from the flange 14 along the upper margins of the projections and are punched inwardly so that the upper edges of the projections engage the under side of the bead 9. The only difference between 15 the punches 21 and the punches 19, 191 is that the punches 21 are formed by cutting through the flange of the cover, whereas the punches 19, 191 are formed by merely indenting the flange from the outside.

20 If the punches 19, 191, 20, 21 and the bead 9 were angular so as to present abrupt shoulders the cover could not be raised until the punches were pressed outwardly, an expedient that has been before resorted 25 to in closure devices of prior construction. In contra-distinction to the former constructions, the rounded character of the punches and bead result in the cover being yieldingly held in closed position.

30 The foregoing described fastening devices or any other suitable cooperating means on the cover and can body may be employed for detachably securing the cover in place.

35 At the present time shippers of lard and similar substances are employing cans of the type manufactured more especially and used for holding garbage. In fact, garbage cans are purchased and the lard or other substances placed in them and shipped.

40 After the substance has been disposed of at retail, the can is sold and is generally purchased for the purpose of holding garbage. Such cans of the usual construction cannot 45 be readily stacked, one upon another, because of the presence of the handle on the covers of the cans. By the construction above described, the covers can be provided with handles and such handles will not interfere with the stacking of the cans.

50 When these cans have been relieved of their contents, they can be sold for the purpose of holding garbage and, if the purchaser desires, he may press the dished portion 16 of 55 the cover upwardly so as to eliminate the dishing in order that rain will not collect on the cover in case of the can being used for garbage and positioned out of doors, as is customary.

60 From the foregoing it will be clear that the can, constructed as above described, is very simple, and is superior in several respects to the cans at present employed for holding lard and the like, since cans of this construction can be stacked one upon an-

other without danger of toppling over and since the covers are temporarily secured in place. This securing of the covers has the two-fold advantage of preventing the covers from readily becoming detached and making the stacking of the cans the more secure, but it is to be understood that the cover fastening feature and the construction of the cover and bottom for stacking can be used independently of one another and also independently of the cover raising device now to be described.

In Figures 1, 6 and 7 the can is provided with a bail 22 which is connected at its opposite ends by bearings 23 to the side wall of the can. One end of the bail 22 is extended to form an arm 24 which may be angular, as shown. In this instance the arm 24 is parallel with the bail and is longer than the distance between the adjacent bearing 23 and the edge of the can when the cover rests on the seat 12 with the punches 19 engaging beneath the bead 9. Thus, when the bail 22 is in its lowered position as in Figure 1, the arm 24 is not in engagement with the cover but, when the bail 22 is raised into substantially a vertical position, as would result in picking up the can by the bail, the arm 24 engages the cover and forces the same upwardly to loosen it from the can body, so that the cover can be readily removed. As seen in Figure 1, when the bail 22 is lowered, the arm 24 hugs the side of the can so that, as the bail is raised, said arm will not fail to engage the cover. To secure this result the bail is sprung to normally hold its ends toward each other when the bail is in lowered position as in Figure 1 and, as the bail springs into position to engage and force upwardly the cover, the arm 24 is forced outwardly by engagement with the side of the can, thus slightly spreading the bail. If the cover were not yieldingly held in place, it could be easily removed by simply raising it by the handle, but being so held, the provision of the arm 24 enables the cover to be forced open with little or no exertion on the part of the operator.

Now referring to Figures 8 and 9, showing a modification of the means for engaging and lifting the cover, the bail is indicated at 25 and is connected by bearings 26 to the side wall of the can. One end of the bail 25 is extended to form an arm 27, similar to the arm 24 excepting that the arm 27 extends at an angle to the bail so that when the bail is moved from a position on the near side of the can in Figure 8 into vertical position, the arm 27 will not engage the can cover. However, the arm 27 is longer than the distance between the bearing 26 and the edge of the cover, when the cover is tightly closed, and thus, if the bail 25 be swung downwardly from its vertical position toward the far side of the can in Figure 8, the

arm 27 will engage the cover and raise and loosen it so that it can be readily removed.

The construction of the bail 22 and arm 24 in Figures 6 and 7 will be preferable if 5 the can is to be used for holding garbage, since the lid will be automatically loosened when the bail is raised into vertical position by the garbage collector as he lifts the can to carry it to the garbage-disposal truck. 10 The construction shown in Figures 8 and 9 will be preferable when the cans are employed in transporting lard and other substances since, in handling the cans, it is undesirable to loosen the covers when the can 15 is being carried by the bail from place to place.

I claim:

A can having a flanged cover fitting over the body of the can, and a bail for the can having an arm at one end to bear against 20 the edge of the cover flange when the bail is moved to position to raise said arm, said bail being sprung to normally hold its ends toward each other when the bail is in lowered position and said arm being forced 25 outwardly by engagement with the side of the can as the bail is swung into position to engage and force upwardly the cover.

Signed at Los Angeles, California, this 23d day of March, 1923.

SIGMUND FREY.
